UNITED STATES PATENT OFFICE.

JONAS NORTHROP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

SELF-THREADING SHUTTLE.

Application filed August 11, 1919. Serial No. 316,546.

To all whom it may concern:

Be it known that I, JONAS NORTHROP, a citizen of the United States, residing at Hopedale, in the county of Worcester and State of Massachusetts, have invented certain new and useful Improvements in Self- Threading Shuttles; and I do hereby declare the following to be a full, clear, and exact description of the invention, such as will enable others skilled in the art to which it appertains to make and use the same.

This invention relates to an improvement in self-threading shuttles for weft replenishing looms.

15 The object of the invention is to provide a thread block for self-threading shuttles of simple construction such that loops which are thrown forward from the bobbin and catch over the beak of the thread block will be thrown off the beak, and also such that the thread will be prevented from escaping from the end of the thread passage nearer the bobbin whereby dethreading of the shuttle is prevented.

20 25 A further object of the invention is to provide a thread block with a leader of improved construction so that the thread may be delivered directly to the shed without going through the delivery eye of the shuttle.

To the accomplishment of these objects and such other objects as may appear, the invention consists in the improved thread block hereinafter described and claimed.

30 35 In the drawings which illustrate the embodiment of the invention in shuttle blocks of two preferred types adapted for use in a left-hand loom and with right-hand wind of bobbin Fig. 1 is a perspective view of a portion of a shuttle illustrating the invention as embodied in one type of thread block; Fig. 2 is a plan illustrating the embodiment of the invention in a different type of thread block; and Fig. 3 is a section on line 3—3. 40 45 Fig. 2.

The self-threading shuttle illustrated in the drawings comprises a shuttle body 10 provided with the usual central opening or chamber 11 for the reception of the bobbin or filling carrier 12. The shuttle body 10 is provided with the usual delivery eye 13 located in the front wall thereof and the filling or thread is led from the bobbin 12 in the chamber 11, into and through the deliv-

ery eye 13 by the improved thread block indicated generally by the reference 14.

The thread block is received into a recess formed in the delivery end of the shuttle, and is held in place by the threaded bolt 15 which passes through a hole in the shuttle body 10, and threads into a nut thereby holding the thread block in the shuttle body 10.

The thread block is provided with the usual longitudinal thread passage 17 running the entire length of the block, and with the usual shield 18 and beak 19. These features of the thread block may be of any desired type, two of which in the present instance, have been illustrated in Figs. 1 and 2, and which are well known and familiar to those skilled in the art and form alone no part of this invention.

The thread block 14 is provided with a guard 20 extended from near the top of the front wall 21 of the thread passage 17, downwardly and toward the rear wall 22 thereof, and then downwardly in a substantially vertical direction to near the bottom of the thread passage 17. At this point the guard 20 is bent around and extends toward the front wall and thence upwards to form a hook 23. The guard 20 forms with the rear wall 22 an inlet conduit 24 through which the filling or thread passes into the interior of the hook 23. The hook 23, and the vertical portion of the guard 20 form an interior thread passage which is in axial alignment with the bobbin 12 and through which the thread normally passes from the bobbin to the delivery eye of the shuttle. The end 90 of the hook 23 is curved as shown in Fig. 2 and is adapted to permit the filling or thread to pass thereover in an easy and uninterrupted manner and also is of such height that after the thread has passed 95 thereover and into the interior thread passage, it is prevented from escape therefrom.

The inlet conduit 24 leads from the top of the shuttle block downwardly in a scroll-like direction into the interior of the hook 100 23, and it is to be observed that the scroll-like shape of the inlet conduit 24 materially aids in leading the thread into the interior of the hook 23, for the reason that as the thread is unwound from the bobbin 12, it 105 naturally assumes a more or less curved or twisting path so that the natural tendency of the thread is to follow the scroll-like con-

duit 24 into the interior of the hook 23. This feature renders the passage of the thread into the interior thread passage of the shuttle positive at all times. Even tension is maintained on the thread as it is drawn from the bobbin 12 to the delivery eye 13 by a loop of felt 25 extended inwardly as illustrated in Figs. 1 and 2 from the inner end of the longitudinal thread passage. The loop of felt 25 is firmly held in an operative position by clamping members 26, 27 so that the thread draws across the felt as it unwinds from the bobbin.

It is apparent that when the invention is embodied in a shuttle adapted for use in a right-hand loom the guard 20 will extend from the rear wall of the thread block and also that the direction of extension of the guard 20 will be changed in both right and left-hand shuttles when a left-hand wind of bobbin is used.

Upon the first pick of the shuttle after replenishment, the filling, unwinding from the bobbin, passes in a longitudinal direction over the top of the shuttle block 14, where it strikes the upper surface of the downwardly curved guard 20, and is guided thereby downwardly toward the mouth of the inlet conduit 24. The filling, as it unwinds from the bobbin, has a definite helical movement, of a greater or less magnitude, which carries the thread through the scroll-like inlet conduit 24 into the interior thread passage within the hook 23. At substantially the same time, the filling passes down over the beak 19, and upon the return pick of the shuttle into the delivery eye 13 in the usual manner. The flat portion of the hook 23 serves as a bearing surface over which the thread normally passes after the shuttle is completely threaded.

As the ordinary shuttle is picked from side to side across the lay with considerable velocity and force, and is stopped very suddenly in the shuttle box at the end of each pick, there is a tendency for the filling or thread as it unwinds to form loops which are thrown toward the delivery end of the shuttle, and which often catch over the beak 19 of the thread block 14 thereby breaking the thread or resulting in the dethreading of the shuttle.

In the present construction, the guard 20 not only serves to diminish the tendency of the thread to form loops by confining it within the thread passage, thus preventing the escape of the thread by ballooning, but also acts as a delooping device, so that if a loop in the thread is formed and on being thrown forward, catches over the beak 19, the guard 20 serves to cause the loop to pass down over the beak so that upon further paying out of the thread during the next flight of the shuttle, the loop is caused to pass around the guard 20 and out over the end of the

hook 23, whereupon the loop is eliminated and the thread continues to run through the interior thread passage to the delivery eye in the usual manner. This feature is conveniently expressed as the delooping feature of the scroll-like guard 20 and is an important feature of the invention for the reason that while the formation of loops in the thread is diminished by the guard 20, any loops which might possibly be formed, are automatically delooped and cannot operate to dethread the shuttle. If by any chance a loop in the thread should be formed directly on the guard 20 it will run off in this manner over the end of the hook 23 and do no harm.

During the operation of the ordinary shuttle it sometimes happens that for one reason or another the thread either escapes from or does not lead through the delivery eye of the shuttle. In this event it may happen that the shuttle will be dethreaded upon the next flight thereof. The present invention provides leading means from which the thread at such times may draw directly without going through the delivery eye of the shuttle and which consist of the vertical and bottom portion of the scroll-like guard 20. It will be observed by reference to Figure 2 that the outer edge of the scroll-like guard 20 is inclined at an angle from the vertical so that the outer edge of the hook portion 23 extends outwardly and upwardly from the lower part of the scroll. It has been found desirable so to incline the outer edge in order that the thread may successfully draw around the scroll as a leader so that the turn of thread around the scroll will not run off and pass over the end of the hook when the scroll is functioning as a leader.

Should the outer edge extend perpendicularly downwardly the turn of thread around the scroll would immediately run off and pass over the end of the hook should it be attempted to make the scroll function as a leader. It will be observed that the thread, after being conducted through the scroll-like inlet conduit 24 into the interior of the hook 23, may draw around either the vertical or bottom portion of the guard 20, as a leader directly into the shed without going through the delivery eye 13 of the shuttle. As the shuttle is picked from one side of the loom to the other, the thread will then be conducted down over the beak 19 and into the delivery eye 13 and the shuttle again threaded in the usual manner. The leading feature of the guard 20 enables the thread to escape from the delivery eye 13 without necessarily dethreading the shuttle or breaking the thread.

It is to be observed then that the guard 20 has three functions: to prevent the escape of the thread from the thread passage

by ballooning or otherwise; to act as a de-looping device; and to act as a leader from which the thread may draw directly to the shuttle without going through the delivery eye thereof.

While the preferred embodiments of the invention have been illustrated and described it is to be understood that the invention may be embodied in other forms within the scope of the following claims:

1. A thread block for self-threading shuttles having, in combination, a longitudinal thread passage, means for guiding the thread to the delivery eye of the shuttle, and a guard for the thread extended from one wall of the thread block transversely across the upper portion of the inner end of the thread passage to near the other wall thereof, and then downwardly to near the bottom of the thread passage and having the lower free end thereof curved to form a hook, said hook having its outer edge inclined upwardly and outwardly to permit functioning of the guard as a leader when the thread does not pass through the delivery eye of the shuttle.

2. A thread block for self-threading shuttles having, in combination, a longitudinal thread passage, means for guiding the thread to the delivery eye of the shuttle, and a guard for the thread extending downwardly from one wall of the thread-block and transversely thereof to form a scroll, the free end portion of which serves as a leader from which the thread may draw directly without passing through the delivery eye of the shuttle.

3. A thread block for self-threading shuttles having, in combination, a longitudinal thread passage, means for guiding the thread to the delivery eye of the shuttle, and a guard for the thread extending from one wall of the thread block transversely across the upper portion of the thread pas-

sage to near the other wall thereof, then 45 downwardly to near the bottom of the thread passage and then upwardly to form a hook, said hook having an upwardly inclined outer edge to function as a leader when the thread fails to pass through the 50 delivery eye of the shuttle.

4. A thread block for self-threading shuttles having, in combination, a longitudinal thread passage and a scroll in the thread passage extended transversely across the 55 thread passage from near the top of one wall thereof and having its free end curved to form a hook, said hook having its outer edge inclined upwardly and outwardly in a manner to permit functioning of the scroll 60 as a leader.

5. A thread block for self-threading shuttles having, in combination, a longitudinal thread passage, means for guiding the thread to the delivery eye of the shuttle, 65 and a guard for the thread extended from near the top of the front wall of the thread passage transversely across the upper portion of the thread passage to near the rear wall thereof, thence 70 downwardly to near the bottom of the thread passage and having the lower portion thereof curved to form a hook, the outer edge of said guard being inclined upwardly and outwardly to cause the guard to function as a leader from which the thread may draw without passing through the delivery 75 eye of the shuttle.

6. A thread block for self-threading shuttles having, in combination, a longitudinal 80 thread passage, means for guiding the thread to the delivery eye of the shuttle, and a scroll within the thread passage having its outer edge inclined outwardly to retain the thread thereon to enable the scroll to 85 function as a leader.

JONAS NORTHRUP.
